INVENTOR:
Roy Fisher,
Somerton
BY
ATTORNEY.

UNITED STATES PATENT OFFICE

ROY FISHER, OF LOS ANGELES, CALIFORNIA

MAIL CARRYING AEROPLANE

Application filed November 10, 1930. Serial No. 494,485.

The object of the present invention is to provide improvements in the construction of mail carrying aeroplanes. More specifically my object is the provision of a substantially fire-proof, light and strong compartment in the fuselage of such aeroplane. A further object is the assembling of such compartment in such a manner as to materially strengthen the framework of the aeroplane. Another object is improved means for locking the compartment of my invention in a fashion acceptable to both users and authorities granting permits for the use of such structures.

15 In the appended drawings, forming part of this specification, is illustrated a structure embodying the invention. The various views of these drawings are as follows:

Fig. 1 is a fragmentary view showing, in perspective, the rear portion of an aeroplane fuselage.

Fig. 2 is a side elevation illustrating the more important parts of Fig. 1.

Fig. 3 illustrates, in perspective, certain interchangeable safety deposit boxes of the structure.

And Figs. 4 and 5 show details of construction, the importance of which will hereinafter appear.

30 The fuselage of the aeroplane may be of any well known construction and it is in Fig. 1 shown to include four corner beams 1, 2, 3, 4, to which all other structural details of the aeroplane may be secured in any approved manner.

The mail compartment of the aeroplane comprises outside plates 5, 6, 7, 8, fastened to said corner beams by suitable means, such as riveting or a welding process. The inner walls of the compartment include plates 10, 11, 12. Between the outer and inner walls are placed layers of heat resisting material, such as asbestos sheets 13, 14, 15, 16, etc.

45 The outer and inner walls of the compartment are made with corrugations, and it is important to note that these corrugations are placed in opposed directions. The corrugations 7^a, of the wall 7, for example, are shown diagonally inclined towards the left, while 50 the corrugations 11^a, of the adjacent plate

11, are shown diagonally directed towards the right. In this manner a very light and strong structure is provided. In the various views of the drawings no attention has been paid to the direction of corrugations in corresponding plates, my aim being merely to emphasize opposed directions.

55 In order to simplify this description, all six sides of the compartment are shown square and of the same size, but they may, of course, be modified to suit particular fuselage design.

The important point I wish to bring out is, that the edges of the asbestos sheets over-lap each other. It is noticed, for instance, that the upper edge of the sheet 13 abuts the inner surface of sheet 16; and that the left edge of the sheet 17 abuts the inner edge of sheet 13; that the upper edge of sheet 14 abuts the inner surface of sheet 17, and so forth. By interlocking the sheets in this manner a very strong and substantially fire-proof structure is provided.

65 The outer walls and the inner walls may consist of separate plates, as aforesaid, or continuous strips of corrugated steel may be bent to provide all four sides of the compartment, if desired. It is important to note that the corrugations do not extend entirely to the edge of the plates, leaving a narrow flat margin around the corrugations for convenience in assembling and fastening to the corner beams, and in order to provide air tight joints. This construction is best illustrated in Fig. 5.

70 The mail compartment of the aeroplane must, of course, be provided with a door. This door may be placed either inside the fuselage or outside, as illustrated in Figs. 1 and 2. The door should also be of double corrugated steel plate construction, and it is provided with a pair of pivotally hung locking levers 20, 21 for engagement with brackets 22, 23 of the wall 5. The levers are shown interconnected by means of a bar 24, on which is fastened a staple 25, adjacent to a staple 26 of the door.

75 A padlock 26 of any approved make is shown engaging these staples for the purpose of maintaining the door locked. The levers 20, 21 and the brackets 22, 23 are shown with

interfitting beveled surfaces for the purpose of drawing the door tightly shut.

As shown in Fig. 2, the compartment is divided into two chambers by means of a partition 27. The larger bottom chamber is of a size to receive mail bags or loose mail in large quantities. The upper chamber is shaped to receive a series of standard size safe deposit boxes 30, 31, etc. For convenience in transferring such boxes from one aeroplane to another, in transit, these boxes may conveniently be insertable within a casing 28 of a size to fit the upper chamber of the compartment. The casing is shown made with a hinged lid 29, the outer end of which is perforated, as at 29^a, for engagement with a staple 30 of the casing. When the lid 29 is closed the staple projects through this perforation far enough to receive the padlock. Or any other suitable device may be embodied for holding a plurality of standard safe deposit boxes.

From the foregoing description it should be clear to those versed in the art, that my object is to provide a mail compartment in an aeroplane for convenience in handling valuable mail and for transferring such mail from one aeroplane to the other. The key to the padlock should, of course, be in the hands of a person authorized to carry such, and the object of providing space for receiving standard size safe deposit boxes is to permit financial institutions, such as banks, to transmit valuables in their own lock boxes. The advantage of this system is readily appreciated. The institutions to which the boxes are addressed, are in a position to send their messengers directly to the landing field to pick up their boxes, thus saving the time ordinarily consumed in routing such mail through the various post office stations.

I claim:

1. In an aeroplane, a mail compartment comprising, outer walls fastened to the corner beams of the plane fuselage, inner walls within said outer walls, and layers of asbestos sheeting intermediate said walls, the adjoining outer and inner walls being provided with corrugations directed in different planes.

2. In an aeroplane, a mail compartment comprising, outer walls fastened to the corner beams of the plane fuselage, inner walls within said outer walls, and layers of asbestos sheeting intermediate said walls, the adjoining outer and inner walls being provided with corrugations directed in different planes, the said corrugations being somewhat shorter than the walls, thereby leaving a flat margin around all four sides of the walls for convenience in assembling and in order to obtain an air-tight joint.

3. In an aeroplane, a mail compartment comprising, outer walls fastened to the corner beams of the plane fuselage, inner walls within said outer walls, and layers of asbestos sheeting intermediate said walls, the adjoin-

ing outer and inner walls being provided with corrugations directed in different planes, and a hinged door in the side of said compartment, said door comprising similarly corrugated outer and inner walls and intermediate asbestos sheets, lock levers on said door for engagement with brackets of said compartment, and means on said levers and the said door for receiving a padlock.

4. In an aeroplane, a mail compartment comprising, outer walls fastened to the corner beams of the plane fuselage, inner walls within said outer walls, and layers of asbestos sheeting intermediate said walls, the adjoining outer and inner walls being provided with corrugations directed in different planes, said asbestos sheets being assembled with overlapping edges, so that the edge of one sheet abuts the inner surface of the adjoining sheet set at right angles thereto.

5. In an aeroplane, a mail compartment comprising, outer walls fastened to the corner beams of the plane fuselage, inner walls within said outer walls, and layers of asbestos sheeting intermediate said walls, the adjoining outer and inner walls being provided with corrugations directed in different planes, there being within said compartment a partition dividing the compartment into an upper chamber and a lower chamber, a casing for insertion within said upper chamber, said casing of a size to receive a plurality of standard size safe deposit boxes, and means for closing and locking said casing for convenience in transferring the casing from one plane to another.

6. An aeroplane fuselage comprising four corner beams extending from front to rear, plates securely fastened to said beams to form a rectangular box, a corresponding inner box, and layers of fire resisting sheets occupying the space between the two boxes, there being in the adjacent outer and inner walls of said boxes corrugations extending in opposed directions, the corners and edges of said sheets being consecutively overlapping so as to form airtight joints.

7. An aeroplane fuselage including four corner beams and being made, intermediate its ends, with a rectangular compartment of which said beams form the four lateral outer corners, said compartment comprising, outer and inner walls, layers of sheets of fire resisting material occupying the space between said outer and inner walls, said sheets being arranged with overlapping edges to form airtight joints, all of said compartment walls being made with corrugations leaving flat margins along all edges in order to provide air-proof joints between walls and the intermediate insulating sheets.

In testimony whereof I have hereunto affixed my signature.

ROY FISHER.
